Stamford, Conn. 06902

Filed Dec. 1, 1965, Ser. No. 14

Term of patent 3½ years

(Cl. D48—2)

FIG. 1

FIG. 2

FIG. 3

FIG. 1 is a front elevation of a candelabrum showing my design;

FIG. 2 is a side elevation of the design illustrated in FIG. 1;

FIG. 3 is a top view of the design illustrated in FIG. 1;
FIG. 4 is a bottom view of the design illustrated in FIG. 1.

The dominant feature of my design resides in the portions shown in full lines. The broken line showing of the lamp bulbs at the apices of the candelabrum arms is for illustration purposes only.

I claim:

The ornamental design for a candelabrum, as shown and described.
